Primary Examiner — Cynthia Ramirez*Assistant Examiner* — Laura H Yu(74) *Attorney, Agent, or Firm* — Nancy J. Flint, Attorney At Law, P.A.; Nancy J. Flint, Esq.(57) **CLAIM**

The ornamental design for a cleaning bucket assembly, as shown and described.

DESCRIPTION

FIG. 1 is a perspective view of a cleaning bucket assembly; FIG. 2 is a rear view thereof; FIG. 3 is a left side view thereof; FIG. 4 is a front view thereof; FIG. 5 is a top view thereof; FIG. 6 is a bottom view thereof; FIG. 7 is a perspective view of a second embodiment thereof; FIG. 8 is a rear view thereof; FIG. 9 is a left side view thereof; FIG. 10 is a front view thereof; FIG. 11 is a top view thereof; and, FIG. 12 is a bottom view thereof.

Right side views not shown are not part of the design sought to be patented. The broken lines in the drawings illustrate portions of the cleaning bucket assembly that form no part of the claimed design.
